UNITED STATES PATENT OFFICE.

HARRISON D. MCFADDIN, OF EAST ORANGE, NEW JERSEY.

DESIGN FOR AN ELECTRIC-LIGHT SHADE.

SPECIFICATION forming part of Design No. 24,473, dated July 16, 1895.

Application filed June 10, 1895. Serial No. 552,341. Term of patent 7 years.

To all whom it may concern,

Be it known that I, HARRISON D. MCFADDIN, a citizen of the United States, residing at East Orange, in the county of Essex and State of New Jersey, have invented a new and original Design for an Electric-Light Shade, of which the following is a specification, reference being had to the accompanying drawings, forming a part thereof, in which—

10 Figure 1 represents a perspective view of the shade, viewed from the open side thereof; and Fig. 2 is a perspective view of the shade, viewed from the closed side.

15 The invention relates to a design for that class of electric-light shades in which a portion of the globe of the light will be exposed.

The design consists in the closed face of the shade provided from top to bottom with a

shell figure A, in which ribs arranged at predetermined intervals apart are made to diverge from the base, being narrowest at that point and widened out to a leaf-like form at their outer or upper ends, the general effect being that of a ribbed-shell, and at the base B of the shade an annular rib C is apparently formed, while the base D from the bottom of the rib is flared outward or rendered more or less bell-shaped.

I claim—

The design for an electric light shade, substantially as herein shown and described.

HARRISON D. MCFADDIN.
